UNITED STATES PATENT OFFICE.

WILLIAM T. MORAN, OF ATLANTIC, MASSACHUSETTS.

PROTECTOR-MASK.

SPECIFICATION forming part of Letters Patent No. 518,822, dated April 24, 1894.

Application filed March 18, 1893. Serial No. 466,589. (No model.)

To all whom it may concern:

Be it known that I, WILLIAM T. MORAN, of Atlantic, in the county of Norfolk and State of Massachusetts, have invented certain new and useful Improvements in Protector-Masks, of which the following is a specification.

This invention has relation to that kind of masks which are devised for the purpose of protecting the face of firemen and others from heat, smoke, and flames, and noxious gases.

It is the object of the invention to provide a mask of the kind mentioned which will perfectly protect the face and other parts of the head of the wearer, and afford an ample supply of fresh air to the mouth and nostrils for breathing purposes.

To these ends the invention consists in the novel construction and arrangement of parts hereinafter described and claimed.

Reference is to be had to the annexed drawings and to the letters marked thereon forming a part of this specification, the same letters designating the same parts or features as the case may be, wherever they occur.

Of the drawings—Figure 1 is a side view of my invention represented as in position on the head of a person, the air tubes reaching to the floor upon which the person stands. Fig. 2 is a vertical sectional view drawn to an enlarged scale, of the invention represented in position on the head of a person. Fig. 3 is a perspective view of the inner crown piece.

In the drawings *a* designates the outer shell which may be of metal, papier-mâché treated so as to be fire proof, or any other suitable material.

b designates an interior crown piece lined with felt or other soft material so as that it may rest easily upon the head of the wearer.

The said crown piece is made so as to fit the upper part of the head of the wearer, and hold the outer shell *a* in position around the head without touching the same. This crown-piece is in the form of an imperforate concaved disk or plate, and is adapted to completely cover the top of the head and protect it.

As shown herein the crown piece *b* consists of a skeleton frame *c* made of wire or other material with projecting ends of the wire frame bent upward vertically as at *d* so as that they may fit in sockets *e* connected with the interior of the shell *a*, and so maintain

the crown piece in position with a space *f* between the same and the outer shell. By this provision opportunity is given for ventilation between the crown piece and outer shell, and the latter should it become heated to an undue extent will not be brought in direct contact with the head of the wearer.

g designates a window arranged in the outer shell opposite the eyes of the wearer, and provided with a sheet of mica or other transparent material which will not be detrimentally effected by moderate heat. The frame of the window *g* is preferably hinged to the outer casing *a* so as that it may be opened when desired or necessary, and thus afford means for wiping perspiration or soot or dust from the window, and also to admit of unrestricted breathing space in case of necessity, without removing the mask from the head.

h designates pipes which communicate with the interior of the outer casing at each side of the same, and preferably opposite the nostrils of the wearer as at *i*, Fig. 3. The said pipes *h* extend from the outer casing to the floor so as that air may be taken into the casing from a point where there is not likely to be smoke or noxious gases. The said pipes may be strapped to the body and legs of the wearer as shown, or they may hang loosely from the casing.

j designates a flexible skirt attached to the lower edge of the outer casing and provided with a draw string *k* so as that it may be tied closely around the neck of the wearer as shown in Fig. 3 to prevent smoke or gases from entering the mask at the neck.

l designates an open top cone or frustum of a cone arranged over a ventilating outlet opening in the top or crown of the casing *a* affording communication between the interior and exterior thereof.

m designates a dome arranged over the open top cone and provided around its lower part with openings *n* as shown, so that air entering the tubes *h* may circulate through the outer casing *a* and escape through the ventilating devices just described in the top of the mask, and prevent smoke from entering the mask at said ventilating devices. This covering of the ventilator in the top of the helmet, so as to prevent smoke and soot from entering the helmet is an important feature.

of the invention. It will be observed that the crown-piece *b* extends over the outlet opening, and hence any matter which might possibly work in through the same is prevented 5 from falling on the wearer's head.

A mask of the character described I have found by experiment to be thoroughly efficient in protecting the face and other parts of the head against undue heat, flame, and smoke. 10 I have also ascertained that by supporting the crown piece *b* in the shell so as that a space *f* may be afforded between the latter and the crown piece, and providing the shell over the crown piece with means for ventilation, that air, to all intents and purposes pure, may be supplied through the pipes *h* to the mouth and nostrils of the wearer to enable the wearer to work with the mask on for an hour or more at a time. If occasion should 15 require the pipes or hose *h* may be sufficiently long to extend out of a window or door, and means may be applied thereto to force air through the pipes to the mask.

Having thus explained the nature of the invention and described a way of constructing 20

and using the same, though without attempting to set forth all of the forms in which it may be made or all of the modes of its use, it is declared that what is claimed is—

A protective mask, comprising in its construction an outer shell adapted to envelop the head of the wearer and provided with transparencies in its front and a ventilating outlet at the top and vertically-extending sockets on its interior above the transparencies, a concavo-convex crown-piece occupying the top part of the mask and having vertical projections which removably engage the sockets in the shell, air-pipes communicating with the interior of the shell at the lower part, 40 and a flexible skirt attached to the lower edge of the shell.

In testimony whereof I have signed my name to this specification, in the presence of two subscribing witnesses, this 3d day of 45 March, A. D. 1893.

WILLIAM T. MORAN.
